VARIABLE INDUCTANCE DEVICE

John W. Hammond, Baltimore, Md., assignor to
 Bendix Radio Corporation, Baltimore, Md., a
 corporation of Delaware

Application July 22, 1938, Serial No. 220,637

3 Claims. (Cl. 171—242)

This invention relates to a variable inductance device and deals particularly with such a device in which variation of inductance is obtained by rotation of a coil structure.

5 An object of the invention is to provide an improved construction in which an electrical contact member is moved along the length of a coil through actuation by rotation of the coil. It is further desired that the electrical contact member be easily movable along the length of the coil independently of the rotation of the coil.

Another object of the invention is to provide a construction in which a resilient brush is held tightly in contact with the coil but wherein the brush is easily slidable lengthwise of the coil without binding or excessive friction. It is desired that the brush be held in place by its own resiliency and be easily removable from the device.

20 A further object is to provide a brush so constructed that if it should be left out of engagement with a turn of the coil, it will assume its proper engagement with a coil turn upon rotation of the coil.

25 Yet another object is to provide an improved coil and brush assembly which is simple and inexpensive to construct and which will not easily get out of adjustment.

The improved construction includes a coil structure rotatably mounted in a frame and a brush bar carried by the frame in spaced relation with the coil structure. Carried between the bar and coil structure is a resilient brush member of improved form which is held in flexed position and which engages a turn of the coil so as to be moved along the coil as the coil is rotated. The improved structure will be more clearly understood by reference to the accompanying drawing in which—

40 Figure 1 is a plan view of the improved device completely assembled;

Figure 2 is a view in side elevation, a part of the coil structure being broken away to show the interior construction thereof;

45 Figure 3 is a detail view of the improved brush structure, the view being taken as seen from line 3—3 of Figure 2; and

50 Figure 4 is a much enlarged sectional view taken at line 4—4 of Figure 3 and showing the engagement of the brush contact element with a turn of the coil winding.

55 As illustrated, A designates a frame; B, a rotatable coil structure; and C₁ and C₂, brushes for making electrical contact at various points along the length of the coil.

The frame A may be of any suitable construction. As here shown, the frame includes a pair of endplates 10 and 11 made of insulating material. Extending between endplates 10 and 11 are the four bars 12, 13, 14 and 15 which secure and support the endplates in spaced relation. Two of these bars, 12 and 13 in the illustrations given, may be constructed of conducting material and may be known as brush bars since they are used also for confining the brushes in position 10 and for providing electrical connection with the brushes.

5 Each of bars 12 to 15 may have their ends secured to the plates 10 and 11 by such means as the screws 16 extending through these plates 15 and into the end portions of the bars. Electrically connected to the bars 12 and 13 are the wires 18 and 17 respectively.

The coil structure B comprises a cylindrical core piece 19 which on its exterior is provided 20 with a helical groove 20 which receives the turns of the coil winding 21. At each end of cylinder piece 19 is a core endpiece 22 to which the endshafts 23 and 23^a are attached. At the rear end of the coil structure the endshaft 23 extends 25 rearwardly through the bearing 24 in the frame endpiece 11 and makes electrical connection with the wire 25 connected to this bearing. At the front of the coil structure the endshaft 23^a extends forwardly through a bearing in endplate 30 10 and has its extreme forward end provided with a slot 28 suitable for receiving the tip of a screwdriver for rotating the coil structure. The rear end of the coil winding 21 is connected to a metallic strip 27 which is secured to the endshaft 23. The forward end of winding 21 may be connected and secured in a similar manner.

The brush structure, C, provided in the improved device, is shown in detail in Figures 3 and 4 of the drawing. As here shown, the brush 40 comprises a strip of resilient material which is arcuate in form and provides the diverging arm members 28 and 29. The end portion of arm 28 is provided with the brush element 30 which has at its tip a groove 31 more clearly illustrated in Figure 4. The edge portions of element 30 on each side of groove 31 are bevelled and have an inclination with respect to the surface of the coil structure such as shown at 32 and 33 of Figure 4. The end portion of arm 29 is provided 45 with the shoe 34 made of insulating material and extending transversely of arm 29. The shoe 34 should be of sufficient length to extend over at least two turns of winding 21 at the several positions of the brush along the coil. At the 50 55

central portion of the brush are the flanges 35 and 36 which extend laterally of the arms 28 and 29 and have their end portions 35^a and 36^a turned upwardly and provided with arcuate recesses 37 suitable for receiving one of the brush bars 12 or 13 therein.

The brush C₁, as above described, may be inserted into position by placing the end portions of arms 28 and 29 in contact with the winding and depressing the central portion of the brushes and bringing the upwardly extended flange ends 35^a and 36^a under the bar 12. Then upon release of the central portion of the brush recesses 37 in flanges 35 and 36 will engage bar 12 and the brush will in this way be held against rotation with the coil structure. With the brush in this position, the arms 28 and 29 will be flexed so as to bear resiliently against the coil winding at their end portions. If the brush element 30 does not happen to receive immediately a turn of winding 21 within its groove 31, only a slight turn of the coil structure B is necessary to bring this element into proper engaging position with a turn of the winding. This automatic engagement of a turn of the winding with the groove 31 takes place due to the presence of the bevelled surfaces 32 or 33. It will be clear that engagement of a coil turn with one of the bevelled surfaces operates to temporarily lift the brush element so as to allow the winding turn to slip into the groove 31. The sides of groove 31, as seen in Figure 4 of the drawing, are of sharp inclination so as to avoid disengagement of the winding turn from the groove upon continued turning of the coil structure.

The improved device may be used with the single adjustable brush C₁, but if desired another brush C₂, of a construction similar to brush C₁, may be added to accommodate another circuit. When, as in the illustrated embodiment, two adjustable brushes are employed, one circuit may be connected by the wires 17 and 25, and another circuit may be connected by the wires 18 and 25. Other connecting arrangements may be used as may be desired.

In the normal operation of the improved coil, the inductance included in each of the above circuits may be changed by rotation of the coil structure B by the use of a screwdriver or other suitable tool inserted in the slot 26 of the end-shaft 23^a. For example, when the end-shaft 23^a is turned in a clockwise direction, each of the brushes C₁ and C₂, being in engagement with a turn of winding 21, will be caused to move longitudinally of the coil to increase the number of turns included between wires 17 and 25, as well as between wires 18 and 25. Turning of the end-shaft 23^a in a counterclockwise direction operates in a similar manner to decrease the inductance presented by the device in both circuits.

When it is desired to increase or decrease the inductance included between conductors 18 and 25, the operator may simply grasp the arm 28 of the brush C₁, and raise the element 30 off the turn of winding 21 with which it was engaged, and then slide the brush member lengthwise of the coil along bar 12 either to add more turns or decrease the number of turns as may be desired. When the arm 28 is again released at the new brush position, the element 30 will again engage a turn of winding 21 either immediately upon release of the arm or upon the initial rotational movement of the coil in obtaining final adjustment. The position of the brush C₂ along the coil 75 may also be changed independently of coil rota-

tion or the position of brush C₁, in the manner such as just described.

The resilient engagement between a turn of winding 21 and one of bars 12 or 13 which is provided by the improved type of brush, makes a very efficient electrical connection between the bar and the winding since the flexed condition of the brush provides a constant pressure tending to maintain the sliding surfaces in good electrical contact. It is also deemed an advantage that only one of the diverging arms on a brush is in electrical contact with the winding, if the end portions of both arms of the brush were to be maintained in electrical contact with the winding. If the end portions of both arms of the brush were to be maintained in electrical contact, mechanical difficulty would be involved in maintaining alignment of the brush, and also electrical difficulties due to such a bridging arrangement would be involved.

Although only one embodiment of the invention has been illustrated, it is clear that many other embodiments might be constructed. Also many changes may be made in the details of construction without departing from the spirit of the invention. The foregoing detailed description has been given for clearness of understanding only and no unnecessary limitations should be understood therefrom, but the appended claims should be construed as broadly as permissible, in view of the prior art.

What I claim is:

1. In an inductance device having a rotatable coil and being variable by rotation of said coil, a contact brush comprising a pair of divergent arms having their end portions engaging said coil, the end portion of one of said arms being electrically insulated from said coil, and the end portion of the other of said arms being in electrical contact with said coil, said arms being resilient, and means slidably engaging said brush for maintaining said arms flexed and bearing against said coil as the coil is rotated, said last mentioned end portion being resiliently releasable from engagement with said coil for adjustment along the coil independently of coil rotation.

2. In an inductance device having a rotatable coil and being variable by rotation of said coil, a contact brush comprising a piece of resilient material, one end portion of said piece being provided with a coil engaging contact element for making electrical contact with said coil, the other end of said piece being provided with a shoe of insulating material and resting upon said coil, and a bar of conducting material disposed longitudinally of and spaced from said coil, said piece having at its middle portion upwardly extending flanges making slidable engagement with said bar, said piece being held in fixed condition by the said bar and coil so as to produce resilient engagement between said brush element and a turn of said coil, said last mentioned engagement being such as to move said piece longitudinally of said coil and along said bar as said coil is rotated.

3. A variable inductance device comprising a frame, a helical coil rotatably mounted in said frame and including a plurality of turns, a brush bar carried in said frame and disposed longitudinally of said coil, a resilient brush carrier slidably engaging said bar, a brush element supported on one end of said brush carrier and engaging said coil, and an insulating shoe mounted on the other end of said brush carrier and bearing against said coil.

JOHN W. HAMMOND. 75
